US0D1057778S

(12) **United States Design Patent** (10) **Patent No.:** **US D1,057,778 S**
(45) **Date of Patent:** **** Jan. 14, 2025**

(54) **3D PRINTER HOUSING**

(71) Applicant: **SprintRay Inc.**, Los Angeles, CA (US)

(72) Inventor: **Hossein Bassir**, Los Angeles, CA (US)

(73) Assignee: **SprintRay, Inc.**, Los Angeles, CA (US)

(**) Term: **15 Years**

(21) Appl. No.: **29/928,226**

(22) Filed: **Feb. 8, 2024**

(51) **LOC (15) Cl.** **15-09**

(52) **U.S. Cl.**

USPC **D15/122**

(57) **CLAIM**

The ornamental design for a 3D printer housing, as shown and described.

DESCRIPTION

FIG. 1 illustrates an elevated right-side perspective view of a 3D printer housing;

FIG. 2 illustrates an elevated left-side perspective view, thereof;

FIG. 3 illustrates a bottom right-side perspective view thereof;

FIG. 4 illustrates a bottom left-side perspective view thereof;

FIG. 5 illustrates a posterior view thereof; and,

FIG. 6 illustrates a bottom view thereof.

The broken lines shown represent unclaimed subject matter and form no part of the claimed design.

1 Claim, 6 Drawing Sheets
